(57) **CLAIM**

I claim the ornamental design for a portable light case, as shown and described.

DESCRIPTION

FIG. 1 is a front perspective view of a portable light case showing a first embodiment of a new design with the case in an open position;

FIG. 2 is a front view of the first embodiment of a new design with the case in an open position;

FIG. 3 is a back view of the first embodiment of a new design with the case in an open position;

FIG. 4 is a top view of the first embodiment of a new design with the case in an open position;

FIG. 5 is a bottom view of the first embodiment of a new design with the case in an open position;

FIG. 6 is a right-side view of the first embodiment of a new design with the case in an open position;

FIG. 7 is a left-side view of the first embodiment of a new design with the case in an open position;

FIG. 8 is a front perspective view of a second embodiment of a new design with the case in a closed position;

FIG. 9 is a front view of the second embodiment of a new design with the case in a closed position;

FIG. 10 is a back view of the second embodiment of a new design with the case in a closed position;

FIG. 11 is a top view of the second embodiment of a new design with the case in a closed position;

FIG. 12 is a bottom view of the second embodiment of a new design with the case in a closed position;

FIG. 13 is a right-side view of the second embodiment of a new design with the case in a closed position;

FIG. 14 is a left-side view of the second embodiment of a new design with the case in a closed position; and,

FIG. 15 is another front view of the second embodiment of a new design with the case in a closed position and in an environment of use.

The broken lines shown represent unclaimed subject matter and form no part of the claimed design.
